TRAVELING PAYOFF DEVICE

Vincent A. Rayburn, Baltimore, Md., assignor to Western Electric Company, Incorporated, New York, N. Y., a corporation of New York

Application April 5, 1954, Serial No. 421,010

4 Claims. (Cl. 242—128)

This invention relates to payoff devices, and more particularly to improved payoff devices designed to travel on a conveyor system. The invention is also concerned with improved braking apparatus for use with such payoff devices.

In some manufacturing operations, a filamentary material, such as steel wire, must be transported in the form of coils from a supply area to a processing area, and there be payed out from a supply stand to a processing machine. For machines which operate continuously it is necessary to connect successive coils to supply the wire without interruption. To satisfy these requirements, the supply and the transportation of the wire must be scheduled carefully. Furthermore, the occurrence of tangles and breaks in the wire must be avoided to prevent interference with such scheduling, as well as to reduce waste.

An object of this invention is to provide new and improved devices for paying off filaments.

Another object of the invention is to provide new and improved payoff devices which travel on a conveyor system.

A further object of the invention is to provide new and improved braking apparatus for use with such payoff devices.

An apparatus illustrating certain features of the invention may include an upright arbor designed to extend axially into and thereby receive a coiled filament to be payed off, a horizontal flyer arm mounted rotatably beneath the arbor for guiding a filament being payed off from the bottom of the coil, and means for suspending the arbor pendant-fashion from the top thereof. Braking means may be included, comprising a braking wheel mounted rotatably on the flyer arm and having its periphery bearing against a horizontal plate so as to roll in a circular path around the plate during rotation of the flyer arm and thereby restrain the speed of rotation of the flyer arm.

A complete understanding of the invention may be obtained from the following detailed description of apparatus forming a specific embodiment thereof, when read in conjunction with the appended drawings, in which:

Fig. 1 is a plan view of a conveyor system having mounted thereon several associated payoff devices embodying the invention;

Fig. 2 is an enlarged view taken along line 2—2 of Fig. 1, with an intermediate portion broken away to conserve space;

Fig. 3 is an enlarged side elevation of a payoff device embodying the invention, with portions thereof shown in section to reveal the internal structure;

Fig. 4 is an enlarged, fragmentary view looking in the direction of the arrows 4—4 of Fig. 3, and

Fig. 5 is an enlarged, fragmentary, vertical section taken along line 5—5 of Fig. 3.

Referring to Fig. 1, a plurality of payoff devices 10, 11, 12, 13 and 14 embodying the invention are shown suspended at different positions along an overhead monorail conveyor track 20. A similar payoff device 15 is de-

2

signed for suspension along the conveyer track 20, but has been shown detached therefrom at a loading station, designated generally by the numeral 40. These payoff devices are essentially nonrotating swifts, which function as traveling wire supply stands, having novel features which give improved operating characteristics. The conveyor system of monorail track and switches on which the devices travel is of conventional construction.

As may be observed from a study of the traveling wire payoff device 12 in Fig. 2, a steel wire 22 is being payed off from a plurality of coils 48—48 of a continuous length of such wire supported on the device 12. For the duration of this operation, the device 12 remains suspended at a selected location on the conveyor track 20, as shown in Fig. 1, and the wire 22 passes through a bellmouthed guide 26 (Fig. 2), which is fixed directly below the device 12 at this location. Thence the wire 22 passes around a sheave 28 and advances to a capstan 30 powered by a motor 32 (Fig. 1). In a similar fashion, a wire 34 is payed off from the device 11, and a wire 36 is payed off from the device 10. The steel wires 22, 34 and 36 are advanced by the capstan 30 to a processing machine (not shown), such as a series of electroplating cells in which a selected metal, for example copper, may be electrodeposited continuously onto the moving wires to produce copper-clad steel electrical conductors.

The devices 10, 11 and 12, from which wires are being payed off, are located on parallel branches of the monorail conveyor track 20. It should be observed that these three devices are staggered laterally with respect to the capstan 30, as shown in Fig. 1, in order to position the wires 22, 34 and 36 being payed off from these devices so that they travel in close side-by-side, parallel relationship as they advance towards the capstan 30. In order to simplify the drawing only three of the devices are shown paying off wire, but to supply some processing machines, such as the series of copper electroplating cells referred to previously, as many as twenty-five or more such devices might be employed to pay off wire simultaneously.

The wire payoff devices 13 and 14 carry additional supplies of wire connected to the wires carried by the devices 11 and 12, respectively, and located in stand-by positions adjacent thereto. The moment the supply of wire being payed off from either one of the devices 11 and 12 becomes exhausted, an automatic change-over is made to the corresponding one of the devices 13 and 14, which is then advanced from its stand-by position to the operating position formerly occupied by the empty device.

One at a time as the devices 11 and 12 become empty, they may be advanced along the conveyor track 20 to a loading station 40 where they may be reloaded with a fresh supply of wire. In Figs. 1 and 3, the wire payoff device 15 is shown positioned at the loading station 40, already loaded and ready to be advanced along the conveyor track 20 to a stand-by position adjacent to the device 10. The bottom or leading end of its supply of wire may then be connected to the top or trailing end of the wire being payed off from the device 10. In this manner a continuous supply of wire is provided without interruption from each of the parallel branches of the conveyor track 20.

It is contemplated that the loading station 40 would be located in a wire storage area remote from the payoff area, to keep the loading operations from interfering or conflicting with the more important payoff operations. Otherwise the loading operators might foul or snare wires payed off and cause accidental breaks or interruptions.

The wire payoff devices 10, 11, 12, 13, 14 and 15 are identical in construction. Details of their construction may be understood readily by reference to the device 15

shown in Fig. 3. In this device, a vertical shaft 42 extends through and is welded to the center of a horizontal disc 44. Extending from points spaced circumferentially near the periphery of the disc 44 are a plurality of staves 46-46, which curve upwardly and converge inwardly to the upper end of the centrally located vertical shaft 42, to which they are all secured by welding. As a group the curved staves 46-46 resemble a generally bell-shaped cage, which together with the disc 44 function as an arbor for supporting a plurality of coils 48-48 of wire thereon.

A lower extension 50 of the vertical shaft 42 projects below the disc 44 and is welded to the center of a horizontal plate 52. The extension 50 is slightly larger in diameter than is the vertical shaft 42, thereby forming a shoulder 54, which bears against the disc 44 and helps to position the disc and to support some of the weight of the disc and the superstructure bearing thereon. A center bar 56 is secured to the bottom of the plate 52.

At the loading station 40, the plate 52 rests on top of a plurality of rolls 58-58 (Fig. 3), which are mounted in two parallel, straight rows, and are journaled between a pair of inner channels 60-60 and a pair of outer channels 62-62. The inner channels 60-60 cooperate with the center bar 56, as shown in Fig. 5, to function as guides which prevent the plate 52 from moving laterally off the rolls 58-58 or rotating on them. In this manner the payoff device 15 is guided lengthwise along the loading station 40. The inner channels 60-60 are spaced apart a distance sufficient to accommodate the center bar 56 during this movement of the payoff device 15.

Each wire payoff device is detached temporarily from the overhead monorail conveyor track 20 while the device is resting on the loading station 40. At all other times, each device is suspended from the track 20 by a plurality of trolley wheels, such as the trolley wheels 64-64 (Fig. 3) on the device 15. The trolley wheels 64-64 are mounted rotatably and pivotally on a pair of yokes 66-66, which together function as a trolley in engagement with the monorail track 20. Details of the manner in which the trolley wheels of the devices engage the track 20 are best shown in the case of the device 12 in Fig. 2.

A load bar 68 (Fig. 3) suspended from the yokes 66-66 is provided with a spherical socket 69, which is connected to a ball 70 secured to the upper end of the vertical shaft 42. The socket 69 and the ball 70 cooperate to form a ball and socket type universal joint. As a result of this arrangement, when the payoff device 15 is suspended from the conveyor track 20, the lower body of the device is supported pendant-fashion and is capable of swinging in any radial direction. The extent of this radial movement is limited by an annular lip 72, which projects from the rim of the socket 69 on the load bar 68, and which is disposed circumferentially around the upper end of the shaft 42. The lip 72 permits the shaft 42 to swivel through a total arc of about 30°.

It should be observed that the load bar 68, together with its trolley wheels 64-64, are considerably smaller in plan area than the arbor formed by the disc 44 and the staves 46-46. This arrangement permits the payoff device 15 to be loaded with a fresh supply of wire by lowering the coils 48-48 of wire over the load bar 68 by means of a grapple 74, of which only the lower portions of three arms 76-76 thereof are indicated in Fig. 3. The load bar 68 and its trolley wheels 64-64 are sufficiently small to pass axially through the coils 48-48 of wire when the grapple 74 is lowering these coils down onto the staves 46-46.

For a portion of the length of the loading station 40 there is a gap in the track 20, so that no overhead track is present at this point to interfere with the loading operation. After the payoff device 15 has been loaded,

an operator pushes this device across the rolls 58-58 towards the end of the leading station 40, where the device will again engage the conveyor track 20 by means of the trolley wheels 64-64.

5 A feature of the present invention is the fact that in paying off wire from coils thereof, such as the coils 48-48, the wire is taken from the bottom rather than the top of the coils. A leading end 80 of the wire being payed off from the coils 48-48 thereof is led from the 10 bottom of these coils through a forked outer end 82 (Figs. 3 and 4), which functions as a wire guide on a flyer arm 84 mounted rotatably on the lower extension 50 of the vertical shaft 42. The flyer arm 84 extends radially outward from the extension 50, and on its inner 15 end is provided with a bearing liner box 86 which substantially completely surrounds the extension 50 and is freely rotatable thereon. At an intermediate point along the length of the flyer arm 84, a roller 88 mounted rotatably thereon, bears against the upper surface of the 20 plate 52. During the rotation of the flyer arm 84, the roller 88 traverses a circular path on the top of the plate 52. In bearing against the plate 52, the roller 88 creates frictional resistance which restrains the flyer arm 84 from rotating too fast. To satisfy this purpose, the roller 25 88 may be made of rubber or be rubber tired, and snubbed with an internal friction brake (not shown).

The forked outer end 82 of the flyer arm 84 extends radially outward beyond the periphery of the disc 44, and near its outer end is bent so that the forked end 30 82 extends angularly upward slightly above the disc 44. This arrangement insures that the forked end 82 of the flyer arm 84 engages and guides the wire, such as the leading end 80 thereof, in such manner that the wire always clears the disc 44. This condition should continue even though the coils 48-48 of wire may sink down further on the staves 46-46 and thereby bring the leading end 80 of the wire closer to the disc 44, in order to allow the wire to pay off from the bottom 35 of the coils 48-48 without interference. The outer edge of the disc 44 is provided with a curved and polished lip 90 which prevents the wire from striking any sharp edges as it is payed off.

The action of gravity naturally causes the convolutions of wire in the coils 48-48 thereof to settle downwardly 45 on the staves 46-46 as the wire is payed off from underneath. The downward movement of the convolutions of wire is further facilitated by the existence of the universal joint formed by the ball 70 and the socket 69, since this permits the lower body of the unit to oscillate 50 freely in any radial direction. By paying off the wire from the bottom of the coils, that being the direction in which the convolutions of wire therein naturally tend to gravitate, the occurrence of tangles and consequent 55 breaks in the wire is greatly minimized.

Apparatus embodying the invention is particularly 60 useful in working with coils of wire in which the convolutions are not all perfectly concentric. The hank-wound bundles of wire produced on the draw blocks of commercial wire drawing machines usually are not concentric. Depending upon the gage of the wire in the 65 bundle, each bundle may contain from about 5 up to about 25 hanks of wire. The length of wire which connects one hank to another in the bundle may extend from the inside to the outside of the bundle. This condition is known in the trade as "false cross-over." It is an inevitable result of the manner in which the wire 70 is coiled as it emerges from the wire drawing machines. Each time a "false cross-over" is encountered in taking wire from the supply stand, there is a possibility that the adjacent convolution of wire may become fouled and snubbed, and thereby snap taut with such suddenness that the wire may break. Such difficulties are substantially 75 eliminated by the use of traveling payoff devices embodying the invention. As added features, the sched-

uling and the transportation of the wire are accomplished with ease.

It is evident that payoff devices embodying the invention are not limited to use in paying off steel wire, but filaments, strands or threads composed of other materials can be handled equally well. Furthermore, the use of a monorail conveyor in association with the invention is not essential, and other types of conveyors could be used. For example, instead of having overhead track, an extensive layout of floor rolls similar to the rolls 58—58 could be used to transport the wire supply units, and a hoist could be used to elevate the units into engagement with an overhead bracket fixed at the payoff location. In fact, no special conveyor is necessary.

It is contemplated that payoff devices embodying the invention should be portable and have means for suspending them pendant-fashion while the coiled filamentary material thereon is being payed off from the bottom of the convolutions thereof. Hence, many structural details may be altered without departing from the spirit and scope of the invention.

What is claimed is:

1. A payoff device, which comprises an upright arbor designed to extend axially into and thereby receive a coil of wire to be payed off, a horizontal flyer arm having one end mounted rotatably beneath the arbor, a wire guide secured to the other end of the arm for guiding a wire being payed off from the bottom of the coil, a horizontal plate secured in spaced relation to the bottom of the arbor, a braking wheel mounted rotatably on the arm and having its periphery bearing against the plate so as to roll in a circular path around the plate during rotation of the arm and thereby restrain the speed of rotation of the arm, and means for suspending the arbor pendant-fashion from the top thereof.

2. A traveling payoff device movable along an overhead conveyor track, which comprises an upright arbor designed to extend axially into and thereby receive a coil of wire to be payed off, a horizontal flyer arm extending radially outward from the bottom of the arbor, said arm having its inner end journaled on the axial center of the bottom of the arbor, a wire guide secured to the outer end of the arm for guiding a wire being payed off from the bottom of the coil, a horizontal plate secured in spaced relation to the bottom of the arbor, a braking wheel mounted rotatably on the arm and having its periphery bearing against the plate so as to roll in a circular path around the plate during rotation of the arm and thereby restrain the speed of rotation of the arm, a trolley movable along said overhead conveyor track, a load bar suspended from said trolley, said load bar having a socket formed therein, and a ball secured to the top of the arbor and engaging the socket to form a universal joint connecting the load bar and the arbor, thereby suspending the arbor pendant-fashion and allowing the arbor to swivel freely while paying off the wire.

3. A traveling payoff device movable along an over-

head conveyor track, which comprises an upright arbor designed to extend axially into and thereby receive a coil of wire to be payed off, a vertical shaft extending axially through said arbor, a horizontal flyer arm extending radially outward from the bottom of the arbor and having its inner end mounted rotatably on said vertical shaft, a wire guide secured to the outer end of the arm for guiding a wire being payed off from the bottom of the coil, a horizontal plate secured to said vertical shaft and in spaced relation to the bottom of the arbor, a braking wheel mounted rotatably on the arm and having its periphery bearing against the plate so as to roll in a circular path around the plate during rotation of the arm and thereby restrain the speed of rotation of the arm, a trolley movable along said overhead conveyor track, a load bar suspended from said trolley, said load bar having a socket formed therein, and a ball secured at the top of the arbor to the vertical shaft, said ball engaging the socket to form a universal joint connecting the load bar and the arbor, thereby suspending the arbor pendant-fashion and allowing the arbor to swivel freely while pay-

ing off the wire.

4. A traveling payoff device movable along an overhead conveyor track, which comprises an upright arbor having a body portion composed of a plurality of staves 25 united in the form of a generally bell-shaped cage and having a base portion composed of a horizontal disc on which the cage is mounted vertically, said arbor being designed to extend axially into and thereby receive a coil of wire to be payed off, a vertical shaft extending axially through said arbor, a horizontal flyer arm extending radially outward from the bottom of the arbor and having its inner end mounted rotatably on said vertical shaft, a wire guide secured to the outer end of the 30 arm for guiding a wire being payed off from the bottom of the coil, a horizontal plate secured to said vertical shaft and in spaced relation to the disc at the base of the arbor, a braking wheel mounted rotatably on the arm and having its periphery bearing against the plate so as to 35 roll in a circular path around the plate during rotation of the arm and thereby restrain the speed of rotation of the arm, a plurality of trolley wheels movable along said overhead conveyor track, a pair of yokes suspended from said trolley wheels, a load bar suspended from the 40 yokes, said load bar having a socket formed therein, and a ball secured at the top of the arbor to the vertical shaft, said ball engaging the socket to form a universal joint connecting the load bar and the arbor, thereby suspending the arbor pendant-fashion and allowing the arbor to 45 swivel freely while paying off the wire.
